VALVE CORE REMOVAL TOOL

John W. Olson, Jr., Garland, Tex., assignor to C & D
Valve Manufacturing Co., Oklahoma City, Okla.

Filed Apr. 18, 1974, Ser. No. 461,973

Term of patent 14 years

Int. Cl. D8—05

U.S. Cl. D8—51

FIG. 1 is a side elevational view of a valve core removal tool embodying my novel design;

FIG. 2 is a front end elevational view thereof;

FIG. 3 is a rear end elevational view thereof;

FIG. 4 is a top plan view thereof; and

FIG. 5 is a bottom plan view thereof.

I claim:

The ornamental design for valve core removal tool, substantially as shown and described.
